DESIGN FOR A TEXTILE FABRIC OR THE LIKE

Robert E. Fatherley, Darien, Conn.

Application June 20, 1933. Serial No. 48,465

Term of patent 3½ years

To all whom it may concern:

Be it known that I, ROBERT E. FATHERLEY, a citizen of the United States, residing at Darien, county of Fairfield, Connecticut, have invented a new, original, and ornamental Design for a Textile Fabric or the like, of which the following is a specification, reference being had to the accompanying drawing, forming a part thereof.

The figure is a plan view of a textile fabric showing my new design. The area within the dot and dash lines shows one complete unit of the design. The repeats are arranged in verti-

cal rows and adjacent vertical rows are one half a complete unit offset so that the angle of the complete unit indicated by letter A corresponds with angle B of one of the repeats in an adjacent vertical row.

I claim:

The ornamental design for a textile fabric or the like as shown and described.

In testimony whereof I have signed this specification.

ROBERT E. FATHERLEY,
